CONSOLE FOR A TYPESETTING MACHINE

Viktor Schreckengost, Cleveland, Ohio, assignor to Harris-
Intertype Corporation, Cleveland, Ohio, a corporation
of Delaware

Filed May 12, 1964, Ser. No. 79,936

Term of patent 14 years

(Cl. D64—11)

FIG-1

FIG-2

FIG-3

FIG. 1 is a perspective view of a console for a typesetting machine, showing my new design;

FIG. 2 is a plan view of the console design shown in FIG. 1; and

FIG. 3 is a view of the rear of the console shown in FIG. 1.

The dominant features of the design are illustrated in full lines in the drawings.

I claim:

The ornamental design for a console for a typesetting machine, as shown and described.
